UNITED STATES PATENT OFFICE.

ADOLF HOLLAND, OF MAGDEBURG, GERMANY.

CENTRIFUGAL MACHINE.

SPECIFICATION forming part of Letters Patent No. 703,728, dated July 1, 1902.

Application filed September 24, 1901. Serial No. 76,353. (No model.)

To all whom it may concern:

Be it known that I, ADOLF HOLLAND, a citizen of the Empire of Germany, residing in Magdeburg, Germany, have invented certain new and useful Improvements in Centrifugal Machines, of which the following is a specification.

This invention relates to improvements in a centrifugal machine employed in separating molasses from sugar, and relates particularly to means for separating the denser from the less dense molasses at the proper stage in the operation of drying the sugar.

To this end the invention consists of a centrifugal machine comprising a casing having a suitably-supported base-plate that is provided with discharge-openings, a rotatable drum mounted in said casing, and an adjustable collecting-plate for guiding the flow of molasses to one or the other of said discharge-openings, as will be more fully described hereinafter and finally pointed out in the claims, reference being had to the accompanying drawings, in which—

Figure 1 is a vertical section of my improved centrifugal machine. Fig. 2 is a horizontal section thereof on line 2 2, Fig. 1. Fig. 3 is a sectional view of the lower part of the casing with the collecting-plate. Figs. 4 and 5 are vertical sections of the machine having modified forms of collecting-plates, and Fig. 6 is a detail view of another form of collecting-plate.

Similar letters of reference indicate corresponding parts.

Referring to the drawings, A represents the cylindrical body portion of the casing of my centrifugal machine, having a suitably-supported base-plate B. Within the casing 40 is mounted upon the vertical rotary shaft S the drum C, the periphery of which consists of perforated sheet metal.

The base-plate B is provided with an upwardly-extending circumferential flange B', 45 which has an interior shoulder upon which the cylindrical body portion A of the casing is seated. Adjacent and concentric to the circumferential flange B' is the partition-flange B'', so that the bottom of the casing is divided 50 into the compartments a and b, having, respectively, the discharge-openings c and d.

The lower edge of the cylindrical body por-

tion A is provided with an inwardly-flaring rim e, that covers the compartment a. This rim e is provided with a plurality of elongated openings k, which are arranged parallel with the edge of the rim and alternately in two concentric circles. An annular collecting-plate f is seated upon the inwardly-flaring rim e and is provided with openings f', 60 similarly arranged to openings k, and between the openings extend the strengthening-ribs l.

The annular collecting-plate f is arranged to have a partial rotary movement, so that 65 the openings k and f' can be caused to register or to be closed. The means for imparting motion to the collecting-plate f consists of the handpiece g, that is connected therewith and projects through the slot A², which 70 is approximately the same length as the openings k and is protected by the guard-plate h, so as to prevent the molasses from passing therethrough. Arranged in the casing at a suitable height and between the drum C and 75 the cylindrical body portion A is a steam-pipe i, that is provided with a plurality of perforations (not shown) that discharge steam outwardly upon the interior surface of the cylindrical body portion of the casing, so as 80 to accelerate the flow of molasses down the interior surface thereof. The molasses that is separated from the sugar flows down the interior surface of the cylindrical body portion A of the casing to the collecting-plate, 85 which, according to the character of the molasses, is directed into the compartment a or b, from which it is passed off through the discharge-opening c or d, so that the molasses containing considerable sugar can be separated 90 from the molasses containing little or no sugar.

As shown in the modification, Fig. 4, the collecting-plate f² is adapted to be raised or lowered by any suitable means, (not shown,) 95 so as to uncover or cover the compartment a. The diameter of the collecting-plate f² is somewhat smaller than the interior diameter of the casing, so that when the collecting-plate is raised there is provided sufficient 100 space between its outer edge and the interior surface of the cylindrical body portion of the casing to permit the molasses to pass into the compartment a, and when the collecting-plate

is lowered the molasses passes over its upper surface and discharges into the compartment *b*.

The modification shown in Fig. 5 is a collecting-plate *f*³, that is also adapted to be raised or lowered in order to direct the flow of molasses through the discharge-openings *c'* or *d'*, while Fig. 6 shows the collecting-plate as being composed of a plurality of segments that are hingeably mounted, so that they can be adjusted to direct the flow of molasses as desired.

Having thus described my invention, I claim as new and desire to secure by Letters Patent—

1. In a centrifugal machine, the combination of a casing having a cylindrical body portion seated in a suitably-supported base-plate, said base-plate being provided with discharge-
openings, a rotatable drum mounted in said casing, and an adjustable collecting-plate disposed below the bottom of said drum for directing the flow of liquid to either discharge-opening, substantially as set forth.
2. In a centrifugal machine, the combination of a casing having a suitably-supported base-plate, said base-plate being provided with discharge-openings, a rotatably-mounted drum in said casing, a partition-flange provided on said base-plate, and an adjustable collecting-plate arranged in contact with the interior surface of said casing and disposed below the bottom of said drum for directing the flow of liquid to either side of said partition-flange, substantially as set forth.
3. In a centrifugal machine, the combination, with a rotatably-mounted drum, of a casing provided with a cylindrical body portion, a base-plate having a circumferential flange and a concentric partition-flange, said

cylindrical body portion being provided with an inwardly-flaring rim extending from said circumferential flange to said partition-flange, said inwardly-flaring rim having a plurality of openings, and an adjustable collecting-plate having openings to register with said openings in the rim, said base-plate having suitably-arranged discharge-openings, substantially as set forth.

4. In a centrifugal machine, the combination of a casing having a cylindrical body, a base-plate having a circumferential flange provided with a shoulder for receiving the cylindrical body portion, a concentric flange adjacent said circumferential flange forming two compartments of said base-plate, each compartment having a discharge-opening, an inwardly-flaring rim provided at the lower edge of said cylindrical body portion and disposed upon said flanges, said rim being provided with a plurality of elongated slots alternately arranged in concentric lines, an adjustable collecting-plate supported on said rim and having similarly-arranged slots, a handpiece connected with said collecting-plate and projecting through an opening in said cylindrical body portion, a cover-plate arranged over said opening for the handpiece, and a steam-pipe arranged in said casing with a plurality of perforations disposed toward the interior surface of said casing, substantially as set forth.

In testimony that I claim the foregoing as my invention I have signed my name in presence of two subscribing witnesses.

ADOLF HOLLAND.
